FIG. 1.

FIG. 2.

FIG. 3.

FIG. 4.

FIG. 5.

FIG. 6.

FIG. 7.

I claim:

The ornamental design for an egg carton lid, as shown and described.
